WALTER A. WOOD, OF DETROIT, MICHIGAN, ASSIGNOR TO GENERAL MOTORS RESEARCH CORPORATION, OF DETROIT, MICHIGAN, A CORPORATION OF DELAWARE.

COMPOSITE PISTON.

Application filed September 7, 1926. Serial No. 134,045.

This invention relates to pistons, particularly that type generally employed in internal combustion engines.

A light weight piston in an explosive engine has been found to be highly desirable, in that it reduces the weight of reciprocating parts, permitting quicker acceleration, greater speed and flexibility, and since the bearing pressure is low the bearings are long lived, friction is reduced, and consequently oil consumption lowered.

In order to produce a piston that will be light in weight yet of utmost strength, aluminum metal or an aluminum alloy has been employed. Aluminum has a high factor or co-efficient of expansion, but it cools quicker than cast iron or steel. Its great heat conductivity lessens carbon deposits on the piston head and they are easily removed. Because of its high expansion, however, an all aluminum piston becomes impracticable since if its clearance in the cylinder is made exact, the expansion under heat results in binding or sticking of the piston in the cylinder, while on the other hand if clearance is not exact the piston slaps against the sides of the cylinder when cold and the clearance allows raw gasoline to seep into the crankcase to dilute the lubricating oil. On the other hand, cast iron pistons are much heavier but they do not have the great degree of expansion so that a close running fit may be had without either slap or binding.

The object of the present invention is to provide a composite piston, which will combine the desirable characteristics of both aluminum and cast iron pistons, without their disadvantages.

In the drawings, wherein is illustrated the preferred, but not necessarily the only embodiment of the invention, Figure 1 is a vertical sectional view of a piston embodying the invention taken on line 1—1 of Figure 2.

Figure 2 is a vertical cross sectional view on line 2—2 of Figure 1.

Figure 3 is a section on line 3—3 of Figure 1.

Figure 4 is a section on line 4—4 of Figure 1.

Fig. 5 is a vertical section showing the invention embodied in another type of piston.

The piston comprises a head 1, and a barrel having an inner and outer wall, which consists respectively of a skirt portion 2

formed integral with the head 1, and a continuous seamless sleeve or shell 3 closely fitted on and surrounding the skirt. The integral head and skirt are preferably formed of aluminum or other light weight metal having similar characteristics. Grooves 4 are provided in the head for locating the customary sealing piston rings to make the piston gas-tight. The shell or sleeve 3, which may be fastened by rivets or otherwise to the skirt, forms a working face or guide for the piston, as it reciprocates within a cylinder. It is preferably formed from steel or other ferrous metal which has a much lower co-efficient of expansion than the aluminum head and skirt. In case an oil ring is used with the piston, a groove 6 may be provided in the skirt which then separates the shell 3 into two bands as shown.

Projecting downwardly from the head 1, but spaced from the skirt portion 2, are a pair of bosses 7—7, with suitable reinforcing ribs 8 and 9, which bosses 7—7 are bored to receive a bearing bushing for mounting the wrist pin of a connecting rod. Openings in opposite sides of the skirt 2 and shell 3 register with the openings in the wrist pin bosses for facilitating the attachment.

Since cast iron or steel has a co-efficient of expansion of only about one half that of aluminum, the clearance between the cylinder and cast iron piston may be comparatively small as compared with aluminum pistons. With the present composite piston, the clearance space will be that of a cast iron piston due to the steel sleeve. The head 1, however, will be a few thousandths of an inch smaller in diameter than the sleeve 3 to permit its expansion, but since the piston will be guided by the sleeve, the smaller diameter of the head will not result in slap. In order to compensate for the difference in co-efficients of expansion between the sleeve and a skirt, the body of the skirt is cut or slotted. One or more such slots may be employed, the desirable arrangement being the use of about six equally spaced longitudinal slots 10 distributed around the skirt 2. In order not to weaken the body of the skirt the slots do not extend from end to end, but terminate at spaced points from the top and bottom extremities. The slots, therefore, permit circumferential expansion of the skirt, that is, the expansion moves toward and fills the slots instead of radially or

outwardly, whereby there is no forcible outward expanding pressure exerted on the sheet metal sleeve 3. To take care of expansion of the skirt at the upper and lower terminals 5 of the slots where there will be little or no circumstantial expansion, the end portions or top and bottom of the skirt are peripherally beveled or tapered inwardly as at 11 and 12, leaving small spaces between the shell 3 and 10 skirt 2 into which the skirt may expand radially. The tapers extend from each top and bottom extremity to points overlapping the slot terminals. Radial or outward expansion 15 will increase the diameter of the beveled ends only a few thousandths of an inch and an inward taper of about .015 will be sufficient. Thus the slots permit the major portion of the skirt to expand circumferentially, without materially weakening the skirt wall because 20 of the closed ends, while such closed end portions are permitted a radial expansion by reducing the diameter for a small extent at such ends, providing clearance between the skirt and shell.

25 The construction of Figure 5 shows the application of the invention to a shorter length piston which does not have an oil groove in the skirt portion and the sheet metal sleeve is undivided. The arrangement is otherwise 30 the same as that before described.

It will thus be seen that the advantages of an aluminum piston and a cast iron piston are combined into one composite piston without the disadvantages of either. The body being 35 of light yet strong material, permits high compression and flexibility of operation. Carbon deposits are less likely to form on the aluminum head and the large area of aluminum permits quick cooling of the piston. The 40 thin sheet metal sleeve gives a smooth working surface to the piston, which may be fitted closely within the cylinder, obviating slap during cold engine conditions or binding when the engine becomes heated.

45 While the construction and arrangement of parts have been described more or less specifically, it is to be understood that obvious modifications may be made as come within the scope of the appended claims.

50 Having described my invention, I claim:

1. A piston comprising a head formed with ring grooves in the peripheral portion thereof, a cylindrical skirt depending from said head and forming a continuation of said peripheral grooved portion, and having a slot 55 extending throughout an intermediate portion and terminating short of the ends thereof, and a sleeve formed of a metal having a lesser co-efficient of expansion than the skirt, 60 closely fitted around said skirt and ending short of the grooved peripheral portion of the head to provide a continuous unbroken working surface for the skirt.

65 2. A piston comprising a head, a cylindrical skirt, integral with and depending from

said head, a continuous unbroken sleeve closely fitted about said skirt and being formed of a metal having a lower co-efficient of expansion than said skirt, said skirt having portions cut away intermediate its ends to provide openings into which the metal of the skirt may move circumferentially to compensate for the relative differential of expansion between the skirt and sleeve. 70

3. A piston comprising a head, a cylindrical skirt, integral with and depending from said head, a continuous unbroken sleeve closely fitted about said skirt and being formed of a metal having a lower co-efficient of expansion than said skirt, said skirt having portions cut away intermediate its ends to provide openings into which the metal of the skirt may move circumferentially to compensate for the relative differential of expansion between the skirt and sleeve, and piston pin 80 bosses carried by said head and extending into, but having no connection with the skirt. 85

4. A piston comprising a head and a skirt having a relatively high coefficient of expansion, said skirt being provided with slots extending throughout a portion of the skirt intermediate the ends thereof, and a continuous unbroken sleeve having a relatively low coefficient of expansion closely fitted on said skirt. 90 95

5. The piston as claimed in claim 4, and piston pin bosses carried by said head, which project within but are independent of said skirt.

6. A piston comprising a head formed with 100 ring grooves in the peripheral wall thereof, a cylindrical skirt depending from and forming a continuation of said wall, piston pin bosses depending from said head and located within but having no connection with said skirt, a sleeve fitted on said skirt and having a lower co-efficient of expansion than said skirt, and means to compensate for the relative differential of expansion between the skirt and sleeve. 105

7. A piston including a head and skirt of light weight metal having a high factor of expansion, a sheet metal sleeve of a smaller factor of expansion fitted over the skirt to afford a working surface, the skirt being inwardly tapered at the margins of the sleeve affording clearance space therebetween, and having a cut extending thru the body of the skirt to points intermediate the tapered portions to accommodate the high factor of expansion of the skirt within the sleeve. 110 115 120

8. A piston including a head and skirt of high heat conductivity, the diameter of the skirt being reduced at the top and bottom of its body and the skirt body having a plurality of slots extending thru-out its length, and a seamless sleeve of uniform diameter thru-out of low heat conductivity fitting over the skirt with its ends at the top and bottom of the skirt whereby the expansion under heat 125 130

moves the skirt into the reduced top and bottom and slotted portions without affecting the sleeve.

9. A piston including a working surface consisting of a thin sheet metal shell having a relatively low co-efficient of expansion and a light weight head and skirt having a high co-efficient of expansion on which skirt said shell is fitted, the end portions of the skirt being of smaller diameter than the remainder of the skirt body whereby radial expansion at the ends will not affect the shell, the remainder of the skirt body having a plurality of spaced openings permitting circumferential expansion of the skirt body.

10. A piston including a working surface consisting of a thin sheet metal shell having a low factor of expansion and a light weight integral head and skirt having a high factor of expansion, on which skirt said shell is carried, the difference in expansion being compensated for by providing slots extending thruout the length of the skirt body terminating away from the skirt extremities to permit circumferential expansion of the major portion of the skirt body, and further providing peripheral inwardly beveled end portions on the skirt body overlapping the slot terminals affording spaces between the shell and

skirt at their respective ends to permit radial expansion without affecting the shell.

11. A piston including a light weight head and integral slotted skirt with depressions at its top and bottom, having a high factor of heat conductivity, and a sheet metal sleeve of a low factor of heat conductivity surrounding the body of the slotted skirt with its ends located over the top and bottom depressions, whereby under heat the slots permit the skirt body to expand circumferentially and the depressions permit radial expansion without affecting the sleeve.

12. A piston including a head and skirt of light metal having a high co-efficient of expansion, a sheet metal sleeve surrounding the skirt and forming a part thereof, having a lesser co-efficient of expansion, the top and bottom portions of skirt being tapered at the ends of the sleeve, and the skirt body having a plurality of longitudinal slots overlapping and terminating intermediate the respective tapered portions, such tapered portions and slots acting conjointly to compensate for the difference in co-efficients in respectively permitting radial and circumferential expansion of the skirt without affecting the sleeve.

In testimony whereof I affix my signature.
WALTER A. WOOD.
